ELECTRIC SWITCH

Filed Dec. 16, 1929

Inventor:
Harry A. Douglas
by L. L. Craig Atty.

UNITED STATES PATENT OFFICE

HARRY A. DOUGLAS, OF BRONSON, MICHIGAN

ELECTRIC SWITCH

Application filed December 16, 1929. Serial No. 414,489.

My invention relates to electric switches and has a number of objects and advantages. In accordance with one characteristic of the invention one member of the switch is inclusive of a metallic fork and the second member is inclusive of a plurality of contacts respectively individual to the branches of the fork. The fork is formed of resilient metal and the branches of the fork are adapted to flex relatively to each other. A switch possessing these characteristics is of particular use where the fork is inclusive of three or more branches which, by being relatively flexible, readily permit of their adaptation to depressions and rises in the parts engaged thereby. One of the switch members is preferably rectilinearly movable and in order that it may be maintained in proper relation to the other switch member a leveling device preferably a spring is employed which is located apart from the places of engagement of the switch contacts. This leveling spring is desirably interposed between both switch members and presses thereupon. This feature of the invention is not to be limited to a switch structure having a fork shaped contacting portion. The movable switch member is preferably provided with a rack thereupon, there being an operating pinion in mesh with the rack. A casing encloses the pinion rack and contacting portions of the switch. The pin is provided with a contractible hub which passes through an opening that is formed in the casing. A switch operating shaft is received by the hub and a clamping collar, upon the exterior of the casing, embraces the hub and clamps it into engagement with said shaft and engages the casing to prevent inward movement of the shaft.

The foregoing and other characteristics of the invention will be more fully explained in connection with the accompanying drawing in which Fig. 1 is a sectional view of a switch which is particularly adapted for assembly with a steering gear housing upon a steering column of an automotive vehicle; Fig. 2 is a sectional view on line 2-2 of Fig. 1; Fig. 3 is a sectional view on line 3-3 of Fig. 1; Fig. 4 is a detail view showing parts of the structure in elevation; Fig. 5 is a sectional

view on line 5-5 of Fig. 1; and Fig. 6 is a perspective view of a portion of the switch member that is provided with a fork shaped contacting element.

The switch illustrated has a member which is inclusive of a horizontally disposed insulating plate 1, spring barrels 2 assembled with this plate and projecting upwardly therefrom, a coiled spring 3 within each spring barrel, a tubular metallic member 4 also with in each spring barrel and in sliding or telescopic relation thereto, each tubular member receiving the corresponding spring 3 therein and a resilient metallic contacting plate 5, which is fixedly secured to all of the tubular members 4 by means of a metallic assembling plate 6 to which the plate 5 is clinched, as indicated at 7. Each tubular member 4 is provided with a flange 8 which is interposed between the plates 5 and 6 and is clamped in place by means of the shoulder 9 which holds the flange against the plate 5. The plate 5 is upwardly bulged at each place thereof that is in alignment with the parts 2, 3 and 4, as indicated at 10, these bulging portions constituting contacting parts. The plates 5 and 6 are of similar fork shape, one plate being placed upon and in register with the other. These plates 5 and 6 are of spring metal, preferably brass, so that the branches of the fork are relatively flexible to permit the contacts 10 to ride over parts engaged thereby, in the operation of the switch, the contacts 10 thus shaping themselves to non-coplanar parts engaged thereby without danger of separating these contacts from parts which they should engage. The other switch member is inclusive of another insulating plate 11, metallic spring barrels 12 mounted upon and projecting upwardly from the plate 11 and metallic contacting bars 13 which are mechanically and electrically united with the two end spring barrels 12. The bars 13 are received within recesses formed within the bottom side of the plate 11. The upwardly spring pressed contacts 14 are received within the barrels 12 and project into the spaces in the enlarged upper ends or extensions of the barrels 12 that receive the metallic ter-

5 minal plugs 15, which are engaged by the contacts 14.

10 The bottom ends of the spring barrels 12 are formed with cavities which are adapted to receive the contacts 10, as will later more fully appear. The insulating plate 1 and the parts thereon are rectilineally movable to bring the contacts 10 into and out of engagement with the barrels 12. These contacts, being upon the outer ends of the branches of the fork shaped member, are adapted to rise and fall relatively as they move into and out of engagement with the barrels 12 that thus constitute contacts 15 supplemental to the contacts 10. These contacts are arranged in a straight row and the barrel contacts 12 are also arranged in a straight row, the two rows being in similar direction and inlapping relation. When the switch is applied to an automotive vehicle one of the bars 13 may constitute a tail light terminal and the other a battery terminal, the intervening spring barrels constituting head light, dimming and parking light contacts.

20

25 The switch illustrated may be provided with a casing 16 of which the insulating plate 11 constitutes a closure. This casing encloses the plate 1 and the parts assembled therewith. Mounting brackets 17 are secured to the casing and serve to mount the same upon the steering gear housing that is assembled with the steering column.

30 The mechanism for moving the movable switch member is desirably inclusive of a rack 35 18 that is formed of a strip of metal which is sinuously curved to form the rack teeth. This rack is desirably carried by the plate 1. A pinion 19 is in mesh with the rack. The casing 16 also encloses said gear elements.

40 A tubular hub 20, formed of resilient metal, is notched, as indicated at 21, to make it contractible. The switch operating shaft 22 is provided with a suitable operating means such as the knob 23 and is passed through an 45 opening, which is formed in the casing 16, and into the hub. A clamping collar 24 embraces the hub and clamps it into engagement with the shaft to prevent inward movement of the shaft. This clamping collar is 50 equipped with a suitable clamping screw 25. Outward movement of the shaft is prevented by the engagement of the hub enlargement 26 with the inner side of the casing 16. The pinion 19 is thus confined to a fixed plane of 55 rotation. In order that the pinion may be readily assembled the combined axial length thereof together with its hub is less than the space between the side walls of the casing 16, so that said hub may be dropped into alignment with the opening in the casing that receives it, when the insulating plate 11 is not in position. The portions of the casing through which the hub 20 passes are laterally deflected and extended as illustrated in Fig. 60 65 5 to form a bearing for the hub.

The springs in the barrel 2 take part in leveling the plate 1. A leveling device, preferably a spring 27, is interposed between and presses upon both of the switch members, the spring 27 being contained within a spring 70 barrel 28 which is assembled with the insulating plate 1. A plunger 29 is telescopically received within the spring barrel 28 and is pressed against the insulating plate 11, or the contacting ends of the spring barrels 12, according to the position in which the plate 1 is placed upon its rectilineal movement that is caused by rotation of the pinion 19. The spring 27 and the parts through which it exerts its pressure are mounted apart from the contacts 10, that is upon one side of this row of contacts so that it readily cooperates with the springs 3 in the barrels 2 to maintain the plate 1 level throughout the entire range of rectilineal movement thereof. 85

The cavities in the bottom faces of the barrels 12 serve to hold the plate 1 and the parts thereon in position when the current conducting contacts are in engagement. Detents 30, which are desirably inwardly bulged portions of the casing 16, enter spaces between the rack teeth to hold the plate 1 in position when the switch is in circuit opening adjustment. These detents may also take part in holding the plate 1 in position when the switch is in circuit closing adjustment. 95

Changes may be made without departing from the invention.

Having thus described my invention, I claim:

1. A switch including one member inclusive of a part in the form of a metallic fork; a second member inclusive of a plurality of contacts respectively individual to the branches of the fork, said members being relatively movable in a direction generally parallel to the plane of the fork and relatively positioned to enable the making and breaking of engagement between said fork branches and contacts; and a leveling spring located apart from the places of engagement of the contacts and fork branches and pressing upon both members. 105

2. The structure of claim 1 wherein the leveling spring is interposed between the switch members. 115

3. A switch including one member inclusive of a part in the form of a metallic fork having three branches; a second member inclusive of a plurality of contacts respectively individual to the branches of the fork, said members being relatively movable in a direction generally parallel to the plane of the fork and relatively positioned to enable the making and breaking of engagement between said fork branches and contacts; and a leveling spring located apart from the places of engagement of the contacts and fork branches and pressing upon both members wherein the fork is formed of resilient metal and the 125 135 145

branches of the fork are adapted to flex relatively to each other.

4. A switch including one member inclusive of a part in the form of a metallic fork; a second member inclusive of a plurality of contacts respectively individual to the branches of the fork, said members being relatively movable in a direction generally parallel to the plane of the fork and relatively positioned to enable the making and breaking of engagement between said fork branches and contacts; and springs, one located at each place of engagement of the contacts with the fork branches and pressing these parts together when in register.

5. A switch including one member inclusive of a part in the form of a metallic fork; a second member inclusive of a plurality of contacts respectively individual to the branches of the fork, said members being relatively movable in a direction generally parallel to the plane of the fork and relatively positioned to enable the making and breaking of engagement between said fork branches and contacts; springs, one located at each place of engagement of the contacts with the fork branches and pressing these parts together when in register; and a leveling spring located apart from the places of engagement of the contacts and fork branches and pressing upon both members.

6. A switch including one member inclusive of a part in the form of a metallic fork having three branches; a second member inclusive of a plurality of contacts respectively individual to the branches of the fork, said members being relatively movable in a direction generally parallel to the plane of the fork and relatively positioned to enable the making and breaking of engagement between said fork branches and contacts; and springs one located at each place of engagement of the contacts with the fork branches and pressing these parts together when in register wherein the fork is formed of resilient metal and the branches of the fork are adapted to flex relatively to each other.

7. A switch including one member inclusive of a part in the form of a metallic fork having three branches; a second member inclusive of a plurality of contacts respectively individual to the branches of the fork, said members being relatively movable in a direction generally parallel to the plane of the fork and relatively positioned to enable the making and breaking of engagement between said fork branches and contacts; springs one located at each place of engagement of the contacts with the fork branches and pressing these parts together when in register wherein the fork is formed of resilient metal and the branches of the fork are adapted to flex relatively to each other; and a leveling spring located apart from the places of en-

gagement of the contacts and fork branches and pressing upon both members.

8. A switch including two contact bearing members relatively movable rectilineally to bring the contacts thereon into and out of engagement; and a leveling spring located apart from the places of engagement of the contacts and pressing upon both members.

9. The structure of claim 8 wherein the leveling spring is interposed between the switch members.

10. A switch including two contact bearing members relatively movable rectilineally to bring the contacts thereon into and out of engagement; a rack and a switch operating pinion meshing with the rack, one of these gear elements being upon one of the aforesaid switch members which is between the other gear element and the other switch member, the latter gear element being mounted apart from the first; and a spring pressing upon both switch members and pressing one of said gear elements upon the other to maintain them in mesh.

11. The structure of claim 10 wherein the spring is between both switch members.

12. A switch including two contact bearing members relatively movable rectilineally to bring the contacts thereon into and out of engagement; a rack and a switch operating pinion meshing with the rack, one of these gear elements being upon one of the aforesaid switch members which is between the other gear element and the other switch member, the latter gear element being mounted apart from the first; a spring pressing upon both switch members and pressing one of said gear elements upon the other to maintain them in mesh; and a detent engageable with the gear element that is upon one of the switch members to hold this member in selected position.

13. A switch including two contact bearing members relatively movable rectilineally to bring the contacts thereon into and out of engagement; a rack upon one of the switch members; a pinion in mesh with the rack; a casing enclosing the pinion, rack and contiguous portions of the switch; a contractible hub for the pinion passing through an opening that is formed in the casing; a switch operating shaft received by said hub; and a clamping collar upon the exterior of the casing and embracing said hub and clamping it into engagement with said shaft and engaging said casing to prevent inward movement of the shaft.

14. A switch including one member inclusive of a part in the form of a metallic fork; a second member inclusive of a plurality of contacts respectively individual to the branches of the fork, said members being relatively movable in a direction generally parallel to the plane of the fork and relatively positioned to enable the making and

breaking of engagement between said fork branches and contacts; and a leveling device located apart from the places of engagement of the contacts and fork branches and engaging upon both members.

15. The structure of claim 14 wherein the leveling device is interposed between the switch members.

In witness whereof, I hereunto subscribe
10 my name.

HARRY A. DOUGLAS.
